UNITED STATES PATENT OFFICE.

HERBERT ANDREW GOTTSCHALK, OF MILWAUKEE, WISCONSIN.

DESIGN FOR A CHRISTMAS ORNAMENT FOR WINDOW DECORATION.

Application filed March 26, 1925. Serial No. 12,896. Term of patent 14 years.

To all whom it may concern:

Be it known that I, HERBERT ANDREW GOTTSCHALK, a citizen of the United States, residing at 508 30th Street, city of Milwaukee, in the county of Milwaukee and State of Wisconsin, have invented a new, original, and ornamental Design for a Christmas Ornament for Window Decoration, of which the following is a specification, reference being had to the accompanying drawing, forming part thereof.

Fig. 1 is a side view in elevation of the ornament, showing my new design.

Fig. 2 is an end view in elevation of the ornament shown in Fig. 1.

I claim:

The ornamental design for a Christmas ornament for window decoration, as shown.

HERBERT ANDREW GOTTSCHALK.
